INFANT'S COMBINED STORAGE CABINET AND CONVERTIBLE BED

Andrew R. Swaney, 43 E. Chalmers Ave.,
Youngstown, Ohio

Filed Sept. 23, 1960, Ser. No. 62,242

Term of patent 14 years

(Cl. D5—5)

FIGURE 3 is a side view of the infant's combined storage cabinet and convertible bed showing the bed elevated to form a chair with tray in vertical guard position.

I claim:

The ornamental design for an infant's combined storage cabinet and convertible bed, as shown and described.
